(57) **CLAIM**

The ornamental design for an equipment for electrical power distribution, as shown and described.

DESCRIPTION

FIG. 1 is a right side isometric view of an equipment for electrical power distribution in accordance with the new design;

FIG. 2 is a right side elevation view thereof;

FIG. 3 is a left side elevation view thereof;

FIG. 4 is a top plan view thereof;

FIG. 5 is a bottom plan view thereof;

FIG. 6 is a front elevation view thereof;

FIG. 7 is a rear elevation view thereof; and,

FIG. 8 is a right side isometric view of the equipment for electrical power distribution of FIG. 1, shown in a typical environment.

The portions of the equipment for electrical power distribution shown in broken lines in FIGS. 5, 7, and 8 represent unclaimed subject matter and form no part of the claimed design.
